INKING ARRANGEMENT OF PLATEN
PRINTING PRESSESFrank Sydney Thompson, Manchester, England,
assignor to T. C. Thompson & Son, Limited,
Manchester, EnglandApplication November 2, 1938, Serial No. 238,312
In Great Britain December 1, 1937

2 Claims. (Cl. 101—340)

This invention has reference to the inking arrangements of platen printing presses, of the kind wherein a rider or smoothing roller arranged to travel with the inking rollers and to rotate in contact with one or more of them has imparted to it an axial to-and-fro movement or reciprocation relative to the inking rollers to ensure uniform inking of the type and wipe out marks.

In the inking arrangements of platen printing presses it is common practice to utilise the rotation of the inking rollers or their runners or of the rider rollers themselves in conjunction with some form of scroll or screw-and-nut mechanism to effect the to-and-fro movement or reciprocation of the rider rollers. Such arrangements have to be kept small to avoid undue weight which is an objection especially in the case of a fast running machine. Further, where a revolving drum is used to supply the ink to the inking rollers (which arrangement considerably reduces the oscillatory travel of the rollers) the revolutions of the inking and rider rollers in their two directions are unequal which necessitates the provision of compensating slip means when the inking rollers are revolved by the drum, and if the drum revolves the rollers in the direction of their downward or inking run (as should be the case) the arrangement is sometimes inefficient owing to the axial movement of the rider rollers being completed, during the downward or inking run of the inking rollers, before the latter reach the type.

The object of the present invention is to provide improved and simple means for effecting the axial to-and-fro movement or reciprocation of the rider roller or rollers that will be free from the disadvantages indicated.

According to the invention the axial to-and-fro movement or reciprocation of the rider roller or rollers is effected through the medium of a rockable member or members pivoted on one or both of the swinging arms which carry the inking rollers and adapted to be rocked about its or their pivot or pivots during the oscillations of said arms.

In the accompanying drawings Fig. 1 is a fragmentary side view and Fig. 2 is a like plan of a platen printing press comprising one embodiment of the invention, Fig. 3 is a side view to a larger scale of one of the end brackets in which the inking and rider rollers are mounted and the associated rod, hereinafter more particularly referred to, for axially reciprocating the rider roller, Fig. 4 is a plan partly in section of the bracket

and Fig. 5 is a view also partly in section of the bracket looking on the left-hand side of Fig. 3.

Referring to the drawings, 6, 7 indicates the side frames of the machine, 8 indicates the fixed platen on which the type is mounted and 9 indicates the movable platen which carries the sheet to be printed. In the side frames 6, 7 arms 10, 11 are pivoted at 12, 13 about which latter the arms are oscillated by means of links 14 (Fig. 1) and cranks 15 fixed on a shaft 16 which is suitably driven from the main shaft of the machine. In the arms 10, 11, which are of channel section, are slidably mounted rods 17, 18 which have mounted on them springs 19, 20 thrusting between the ends 10a, 11a, of the arms and collars 17a, 18a, fixed on the rods 17, 18 so as to urge the latter inwards.

The outer ends of the rods 17, 18 carry saddles or hooked brackets 21, 22 which are rockably mounted on pivots 23, 24. The ends of the rods 17, 18 are formed with tongues 17b, 18b, which take into slots 21a, Fig. 5, in the saddles or brackets 21, 22. The pivots 23, 24 are formed with collars 23a, 24a, which are secured to the saddles or brackets 21, 22 by screws 21b, Fig. 5, and also with extensions 23b on which lugs 25, 26 are mounted and secured by nuts 23c, 24c.

The spindles 21a, 28a of the inking rollers 21, 28 are rotatably mounted in the saddles or brackets 21, 22 and between the inking rollers a rider roller 29, adapted to be pivotably rotated by and in contact with said rollers, has its spindle 29a slidably mounted in the lugs 25, 26.

On the oscillatory arm 10 the shorter arm of an L-shaped lever 30 is pivoted at 31. In the longer arm of the lever 30 is slidably mounted a rod 32 having its outer end formed with a yoke 33 through which the spindle 29a of the rider roller 29 extends. The spindle 29a is retained in the yoke 33 by a keep 34 and collars 35, 36 are fixed on the spindle one on either side of the yoke. At the junction between the arms of the lever 30 there is pivoted at 37 one end of a link 38 the other end of which is pivoted at 39, a little below the pivot 12 of the arm 10, in a bracket 40 fixed on the side frame 6.

During reciprocation of the arms 10, 11 between their extreme positions indicated by the dot-and-dash lines X, X¹, Fig. 1, the inking rollers travel to and fro between the positions indicated in dotted lines at Y, Y¹ and the rider roller 29 travels in the same path as, and rotates in contact with, the inking rollers in the usual way. Owing to the eccentricity of the pivot 39 of the link 38 relatively to the pivot 12 of the

- arm 10, the pivot 31 of the lever 30 moves in arcuate path Z, Fig. 1, about the centre 12 while the pivot 37 of the link moves in the arcuate path Z¹ about the centre 39. The effect of the 5 relatively eccentric paths of the pivots 31, 37 is that during the downward movements of the arms 10, 11 and inking rollers 27, 28 from the positions X, Y, Fig. 1, to the positions X¹ Y¹, the lever 30 is caused to rock on its pivot 31 and 10 reciprocate the rider roller 29 away from the observer in Fig. 1, i. e. in the direction indicated by the arrow W in Fig. 2, and during the return movements of the arms 10, 11 and inking rollers 27, 28 from the positions X¹, Y¹, Fig. 1, to the 15 positions X, Y, the lever 30 is caused to rock on its pivot 31, in the opposite direction to formerly, and reciprocate the rider roller 29 towards the observer in Fig. 1, i. e. in the direction indicated by the arrow W¹ in Fig. 2.
- 15 20 When the inking rollers 27, 28 are in the position indicated in dotted lines at Y, Fig. 1, they contact with, and are frictionally driven by, and pick up ink from, the positively driven drum 41. The drum 41 is driven and has ink supplied 25 to it in the known ways.
- 20 25 The spindle 29a of the rider roller 29 is free to move laterally in the yoke 33 in order that it may partake of the pivoting movements of the inking rollers 27, 28 and the saddles or brackets 21, 22 about the pivots 23, 24 of the latter, and so maintain itself in proper engagement with the inking rollers.
- 25 30 If desired the oscillatory arm 11 may also have associated with it means as described for reciprocating the rider roller 29. In such case the pivot corresponding to the pivot 39 of the

lever 38 will be arranged at a corresponding point above the pivot 13 of the arm 11.

It will be apparent that by appropriate multiplication of the mechanism described, or coupling together two or more such mechanisms, two or 5 more rider rollers may be given axial to-and-fro motions or reciprocations in union or independently of each other.

I claim:

1. In the ink spreading arrangement of a 10 platen printing press, including a reciprocating member pivoted on the frame of the press and carrying a plurality of ink spreading rollers, an L-shaped member one arm of which is pivoted at a point on said reciprocating member, the other 15 arm of which is connected to one of said rollers, and a link pivoted at one end to the frame on an axis noncoincident with that of the reciprocating member and pivotally attached at its other end to the L-shaped member, whereby upon recipro- 20 cation of said reciprocating member a lateral motion is given to the one of said rollers relative to the others.

2. In the ink spreading arrangement of a 25 platen printing press, including a reciprocating member pivoted on the frame of the press and carrying a plurality of ink spreading rollers, an L-shaped member one arm of which is pivoted at a point along the axis of said reciprocating member, the other arm of which is connected to 30 one of said rollers and the juncture of the two arms of which is connected by a rod to the frame of said press in a vertical line with and below the point of support of said reciprocating member, whereby a lateral motion is given to one of 35 said rollers relative to the others of said rollers.

FRANK SYDNEY THOMPSON.
